UNITED STATES PATENT OFFICE.

FRANK A. STECHER, OF ROCHESTER, NEW YORK, ASSIGNOR TO STECHER LITHOGRAPHIC COMPANY, OF ROCHESTER, NEW YORK, A CORPORATION OF NEW YORK.

CURING-MACHINE.

1,190,337.

Specification of Letters Patent.

Patented July 11, 1916.

Application filed April 15, 1915. Serial No. 21,568.

To all whom it may concern:

Be it known that I, FRANK A. STECHER, of Rochester, in the county of Monroe and State of New York, have invented certain new and useful Improvements in Curing-Machines; and I do hereby declare the following to be a full, clear, and exact description of the same, reference being had to the accompanying drawings, forming a part of this specification, and to the reference-numerals marked thereon.

My invention relates to curing machines with more particular reference to the type of apparatus employed for treating sheet material, and embodying generally a retaining mechanism for supporting sheets of paper or similar material in suspended or vertical position while subjecting them to currents of air possessing certain determinable degrees of temperature and moisture in order to produce a standard condition in the stock undergoing treatment, and the present structure has for its purpose to provide a novel arrangement whereby an even, regular effect is assured throughout all parts of the sheet.

Another purpose of the structure is to effect a more complete and thorough intermingling of the air with the material under treatment so that one portion of any given sheet will be subjected to precisely the same amount of heat and moisture as any other portion, and the different sheets, at the same time, will have imparted to them a uniform treatment.

A further object contemplated by this improvement is to so direct the air as it is discharged into contact with the material that it is distributed over a large space, and is of maximum efficiency with relation to the area of surface which it engages.

To these and other ends the invention consists in certain improvements and combinations of parts all as will be hereinafter more fully described, the novel features being pointed out in the claims at the end of the specification.

In the drawings: Figure 1 is a view in side elevation, with parts broken away, showing a machine constructed in accordance with the invention; Fig. 2 is a side elevation; Fig. 3 is a plan view of the air duct, and Fig. 4 is a sectional view on the line 4^a—4^a of Fig. 3.

Similar reference characters in the several figures indicate the same parts.

The invention is susceptible of a variety of uses and as an instance of its application, I may cite the lithographic art in which difficulty is experienced in properly matching sheets after they are printed, owing to the changes that occur in the paper either from shrinkage or expansion resulting from atmospheric conditions in the printing room. In order to overcome this, it is necessary to previously subject the paper stock for a considerable length of time to currents of air of substantially the same temperature and humidity as that of the press room, thus curing it, or fixing the fibers of the paper so that a definite standard can be maintained throughout the entire printing operation to prevent the sheets from varying in the slightest degree as to size. Various machines have been designed having this purpose in view and the present apparatus contemplates more especially a means whereby to insure properly curing the stock by effecting a maximum intermingling of the air, as distinguished from other forms of apparatus in which the air is distributed in such manner as to effectively treat some parts of the material more than others and by operating with the mechanism which I am about to describe, the necessary treatment of the paper or other material can be completed in a minimum period of time.

With these ends in view, the structure comprises sheet holding means adapted for maintaining a plurality of sheets in suspended or vertical position, and preferably consisting of an endless conveyer which travels about sprocket wheels 1 and 2 and may be driven in any suitable manner so as to effect continuous travel of the conveyer. The latter may be of any desirable form and in the present instance, includes a series of rods carrying rollers 3. The rods are connected together, each carrying a pair of clamps consisting of a stationary jaw 4 and a hinged jaw 5 operating by gravity to engage a series of sheets shown at 6. The lower lap of the conveyer is supported and travels upon angle bars 7 engaged by the rollers 8, while the upper lap travels on the angle bars 8 which constitute a support for the same. It will be understood that the features of construction of the conveyer which I have just

described constitute no part of the present invention except in so far as they afford generally a means for maintaining the sheets in vertical position with reference to the air currents, the distribution of which is now to be described.

The air distributing means includes an air duct 9 extending lengthwise of the machine, and supplied with air from any suitable pressure or blowing apparatus, the air being maintained at any desired degree of temperature and humidity which will vary under different conditions and be determined by the particular quality which it is desired to impart to the stock. The duct 9 may be provided with conduits 10 leading thereto and supplied from a blower 11. Air is discharged from the duct 9 upwardly, in such a way as to thoroughly agitate the sheets and come in contact with every portion of the surfaces thereof and with this in view, I employ a series of discharge ports 12 arranged at the sides of the duct and directed inwardly toward the center and also upwardly. The ports 12 embody narrow elongated openings connected with the duct 9 by curved walls 13 and 14 which are so formed as to permit ready passage of the air and prevent the formation of air pockets. The ports 12 are arranged at opposite sides of the duct 9 and in alternate relation, as shown in Fig. 3 whereby the sheets are successively subjected to oppositely directed currents for predetermined intervals, depending on the speed of travel of the conveyer. Combined with the inwardly moving currents of air which issue from ports 12 are additional air currents traveling entirely in an upward direction and issuing from ports 15 which are disposed between the side ports 12. The ports 15 are preferably narrow and continuous, extending throughout the length of the duct 9, while they are connected to the main body of the duct by curved walls 16. Although I have shown in the present disclosure two ports 15, it may not be entirely necessary to employ both of these under all conditions, as some requirements may obtain where only one vertically directed port may be necessary, which could be arranged centrally of the duct 9. Further, it is not absolutely essential that the ducts 15 be continuous, since a series of openings in spaced relation to each other might be sufficient for some purposes although I prefer to make use of the particular arrangement shown and described. The top wall of the duct 9 is connected with the side walls by means of curved portions 17, eliminating sharp corners or pockets entirely from the air conduit, so as to obviate dead air spaces within the chamber and to reduce friction to a minimum.

I claim as my invention:

1. A curing machine comprising sheet holding means for maintaining a sheet in a vertical position, and an air duct arranged beneath the sheet holding means and provided with upwardly and inwardly directed ports at its sides acting to cause air to be projected upwardly, and inwardly from the sides, into contact with the sheet.

2. A curing machine comprising sheet holding means for maintaining a sheet in a vertical position, and an air duct arranged beneath the sheet holding means and provided with upwardly and inwardly directed ports at its sides and upwardly directed ports between its sides acting to cause air to be projected upwardly from the center, and upwardly and inwardly from the sides into contact with the sheet.

3. A curing machine comprising sheet holding means for maintaining a sheet in a vertical position, and an air duct arranged beneath the sheet holding means and provided with upwardly and inwardly directed ports arranged in alternate relation at opposite sides and upwardly directed ports between the sides acting to cause air to be projected upwardly from the center and upwardly and inwardly from alternately arranged portions of the sides.

4. A curing machine comprising sheet holding means for maintaining a sheet in a vertical position, and an air duct arranged beneath the sheet holding means and provided with upwardly and inwardly directed elongated ports arranged in alternate relation at opposite sides and an upwardly directed continuous port arranged between the sides.

5. A curing machine comprising a traveling conveyer for holding sheets in a vertical position, and an air duct arranged beneath the conveyer and provided with upwardly and inwardly directed ports at its sides acting to cause air to be projected upwardly and inwardly from the sides into contact with sheets on the conveyer.

6. A curing machine comprising a traveling conveyer for holding sheets in a vertical position, and an air duct arranged beneath the conveyer and provided with upwardly and inwardly directed elongated ports arranged alternately at opposite sides and an upwardly directed continuous port arranged between the sides acting to cause air to be projected upwardly at the center and upwardly and inwardly from the sides of the duct into contact with sheets on the conveyer.

FRANK A. STECHER.
